E. P. LINDAHL.

BOTTLE CASE.

APPLICATION FILED MAR. 22, 1917.

1,315,371.

Patented Sept. 9, 1919.

Inventor:

Erick P. Lindahl,
by S. T. Verbeck
his Attorney.

UNITED STATES PATENT OFFICE.

ERICK P. LINDAHL, OF PLEASANT RIDGE, OHIO, ASSIGNOR TO THEODORE HAUMESSER,
OF PLEASANT RIDGE, OHIO.

BOTTLE-CASE.

1,315,371.

Specification of Letters Patent.

Patented Sept. 9, 1919.

Application filed March 22, 1917. Serial No. 156,624.

To all whom it may concern:

Be it known that I, ERICK P. LINDAHL, a citizen of the United States, residing at Pleasant Ridge, in the county of Hamilton and State of Ohio, have invented certain new and useful Improvements in Bottle-Cases, of which the following is a specification.

My invention relates to cases such as are usually employed as receptacles for milk bottles and other bottles and the like, and which for the sake of brevity will be herein-after referred to as a bottle case, and has for its object the provision of novel bracing and connecting means for the walls of the case for providing a substantial and rigid construction. It is a further object of my invention to provide means whereby the cases, if it is desired to stack the same in superposed relation for economizing in floor space, will be positively positioned in vertical alinement relative to one another.

Other objects of my invention will be readily understood from the following description and claims, and from the drawings, in which latter:

Figure 1 is a fragmentary perspective view of bottle cases constructed in accordance with my invention and stacked one upon the other.

Fig. 2 is an end elevation of a bottle case, partly broken away.

Fig. 3 is a similar side elevation.

Fig. 4 is a plan view of a corner of a bottle case, partly broken away and partly in section on the line 4—4 of Fig. 2, to expose the corner member connecting the walls of the case.

Fig. 5 is a vertical section through a corner of a bottle case, taken in the plane of the line 5—5 of Fig. 4.

Fig. 6 is a top perspective view of one of the corner pieces of the bottle case; and,

Fig. 7 is a bottom perspective view of the same.

The bottle case is exemplified as comprising walls 11, 12, forming the sides and ends of the case respectively. The ends of the side-walls are preferably received across the butt-ends of the end-walls with the proximate ends of connecting walls joined by corner-pieces 13, which are instanced as formed of a suitable metal, preferably cast iron. Handle openings 18 may be provided

in the end-walls of the bottle case. The supporting means for the bottles adapted to be received in the case, may be of any well-known construction, instanced as sets of parallel wires 14, 15, connected to opposite walls of the case, and respectively forming bases upon which the bottles are adapted to rest, and partitions which are arranged to laterally position the respective bottles upon their supporting bases.

Corner-pieces 13 are adapted to be forced into wedging contact with the ends of connecting walls of the case, to form a rigid connecting means for the walls, and are also adapted to form bracing means at the corners of the case when the latter is assembled. For this purpose the corner-pieces are exemplified as each comprising diverging sides 16, 17, and webs 19, 20, projecting laterally from the respective diverging sides. The sides 16, 17, are arranged to form a brace adapted to be received within a corner of the assembled bottle case in contact with the respective walls 11, 12, forming said corner, and webs 19, 20, are so arranged relative to sides 16, 17, as to engage the respective walls 11, 12 forming said corner, the ends of walls 11, 12, being instanced as provided with slots 25, into which the respective webs are adapted to be forced in an endwise direction when assembling the bottle case.

The laterally extending webs of the corner-pieces preferably extend outwardly therefrom intermediate of the upper and lower edges of angularly diverging sides 16, 17, so that said sides may engage walls 11, 12, forming the corners of the bottle case, above and below the webs for forming rigid bracing and connecting means for the corners of the bottle case.

In order to provide a wedging engagement between the webs of a corner-piece and the walls of slots 25 in which the webs are adapted to be received, the outer side edges of the webs are instanced as provided with transverse flanges 26 forming overhanging shoulders 27 shown inclined at their inner faces and arranged to wedgingly engage the walls of slots 25.

The inner edges 28 of the shoulders are preferably formed to compress the outer ends of the walls of the slots 25 for compressing the wood of the respective walls

of the case at said slots and to cut away the surplus wood at said edges. The inner ends 29 of the webs are preferably sloped at an acute angle to the outer faces of the flanges 5 for forming said cutting edges 28. Firm connection between the corner-pieces and the material of the walls of the case is thus formed.

The inner ends of the slots at the outer 10 faces of the walls of the case, are preferably enlarged as shown at 31, in order to limit the extent of any slivering or splintering of the wood at the outer ends of the side walls of the slots in said walls, which may 15 take place occasioned by the entering of the webs and flanges thereon, into said slots.

The corner-pieces of the bottle case are adapted to form positioning lugs 32 for aiding in stacking the cases one upon the other, 20 the lugs being instanced as comprising the upper ends of the angularly diverging sides of the corner-pieces which are exemplified as elongated so that the angular lug formed thereby will project above the upper edge 25 of the bottle case. The outer faces of the lugs, are instanced as slightly inwardly offset from the outer faces of the diverging sides of the corner-pieces, as shown at 33, whereby the corners of a bottle case may be 30 readily received over the lugs of the next lower case of a stack, without binding against the faces of said lugs, but in close proximity thereto so that the lugs will form 35 positioning stops to aid in proper stacking of the cases.

Reinforcing strips, which may be of suitable metal such as steel, are preferably provided for the walls, and at the corners of the cases. These reinforcing strips are instanced 40 as flat strips 37 secured upon the upper and lower edges of the side-walls, and cross-sectionally flat bands 38 secured upon the upper and lower edges of the end-walls, and received about, and secured to, the end portions 45 of the side-walls extending across the butt-ends of the end-walls as hereinbefore described, the reinforcing bands thus binding together the corner-forming walls to provide a rigid construction. Reinforcing 50 strips 37 upon the edges of the side-walls are instanced as overlapped at their ends by the reinforcing bands thus received across the end portions of the side-walls.

Nails 44 are instanced as employed for se- 55 curing reinforcing strips 37, 38, to the walls of the cases, the nails used for fastening strips 38 to the end portions of the side-walls of the cases, preferably extending through the side-walls and into the butt-ends of the 60 end-walls received against the same, to more firmly connect the walls of the case at the corners formed thereby.

Rabbets 39, 40, are preferably formed in the outer faces of the end portions of the 65 side-walls beneath reinforcing bands 38,

and in the proximate outer edges of the webs of the corner-pieces which are received in the slots in the side-walls, and which are instanced as the webs 19, the rabbets being arranged to accommodate the reinforcing 70 bands, so that their outer faces are in substantially the same plane as the outer faces of the side-walls. The ends of the reinforcing strips upon the edges of the side-walls and across which reinforcing bands 38 ex- 75 tend, are preferably received in rabbets 41 at the ends of the edges of the side-walls, so that the ends of the reinforcing strips are offset as shown by the bends 42, whereby the outer faces of the reinforcing bands received 80 across said offset portions, will lie in substantially the plane of the outer faces of reinforcing strips 37. Wearing surfaces positioned in substantially the same plane throughout are thus provided upon the edges 85 of the bottle cases for engagement by the positioning lugs and the wearing surfaces, of the adjacent cases of a stack.

Having thus fully described my invention, what I claim as new and desire to secure 90 by Letters Patent, is:

1. A receptacle of the character described, said receptacle comprising walls forming corners, and corner-pieces at said respective corners, each of said corner-pieces comprising an inner angle-portion provided with engaging faces at substantially right angles to each other, a web extending at substantial right angles from each of said engaging faces, and a flange at the outer edge of each 100 of said webs, said flanges extending at substantial right angles to each other, said webs received through the respective walls of the corner, with said engaging faces and said flanges respectively at the inner and outer faces of said respective walls, constructed and arranged for bracing said receptacle and connecting proximate ends of said walls, said corner-pieces extending beyond said receptacle for forming positioning means between said receptacle and the next adjacent receptacle of said stack. 105

2. In a bottle case, the combination of walls forming a corner, a slot in the end of each of said walls at said corner, a corner-piece, said corner-piece comprising engaging faces engaging the inner faces of said walls at said corner, webs extending at substantial right angles from said respective engaging faces received in said respective 115 slots, and flanges extending at substantial right angles to each other at the outer edges of said webs engaging the outer edges of the walls of said slots, for clampingly holding said last-named walls between said engaging faces and flanges, said flanges respectively spaced from the point of said corner a distance substantially equal to the thickness of said respective first-named walls, said corner-piece provided with a rabbet between 120

125

130

said point of said corner and one of said flanges, and a strengthening strip received in said rabbet.

3. In a bottle case, the combination of walls forming corners by end-abutment of one of said walls against the inner face of the other of said walls at said respective corners, slots in said walls at said corners, corner-pieces, said corner-pieces provided with side-webs in said slots, engaging faces engaging the inner faces of said walls at said corners, and flanges at the outer edges of said webs engaging the walls of said slots for clampingly holding said last-named walls between said faces and flanges, that web of each of said corner-pieces which is in the slot of the wall against which end-abutment is made being provided with a rabbet, and reinforcing strips received about the respective corners and in said rabbets.

4. A corner-piece of the character de-

scribed comprising an angle-portion provided with engaging faces at substantial right angles to each other adapted to engage the inner faces of the corner of the receptacle, a web extending at substantial right angles from each of said engaging faces, said webs extending at substantial right angles to each other, a flange at the outer edge of each of said webs, said flanges extending at substantial right angles to each other, said flanges spaced from the point of said corner, and a rabbet between said point and one of said flanges.

In testimony whereof, I have hereunto signed my name in the presence of two subscribing witnesses.

ERICK P. LINDAHL.
